Filed June 30, 1966, Ser. No. 2,879

Term of patent 3½ years

(Cl. D34—5)

FIG. 1 is a perspective view of a golf club or similar article showing my novel design and looking from above the head and in front of the club on the side opposite the face of the club, a section of the shaft being broken away for convenience of illustration;

FIG. 2 is a bottom view thereof;

FIG. 3 is a rear end view of the head of the club looking along the bottom edge thereof;

FIG. 4 is a front end view of the head of the club; and

FIG. 5 is a side elevational view looking at the face of the club.

The dominant features of the design reside in the portions shown in full lines in the drawing. In FIGS. 3, 4, and 5 the shaft is shown broken away for convenience of illustration.

We claim:

The ornamental design for a golf club or similar article, substantially as shown and described.
